W. S. BURGESS,

**AIRPLANE CONTROL SURFACE OPERATING BRACE.
APPLICATION FILED MAY 31, 1918.**

1,357,950.

Patented Nov. 9, 1920.

UNITED STATES PATENT OFFICE.

WILLIAM STARLING BURGESS, OF MARBLEHEAD, MASSACHUSETTS, ASSIGNOR TO
CURTISS AEROPLANE AND MOTOR CORPORATION, A CORPORATION OF NEW
YORK.

AIRPLANE-CONTROL-SURFACE-OPERATING BRACE.

1,357,950.

Specification of Letters Patent.

Patented Nov. 9, 1920.

Application filed May 31, 1918. Serial No. 237,460.

To all whom it may concern:

Be it known that I, WILLIAM S. BURGESS, a citizen of the United States, residing at Marblehead, in the county of Essex and State of Massachusetts, have invented certain new and useful Improvements in Airplane-Control-Surface-Operating Braces, of which the following is a specification.

This invention relates to airplane details. 10 The particular part or element of the airplane to which the inventor has reference is that part known as the rudder operating brace or "yard arm." Such part ordinarily comprises opposed lever arms or horns, control leads, and wire stays which brace the control surface by connection with the lever arm at one end and with the control surface at the other. Accordingly as the control leads are manipulated and placed under tension the resulting stress is uniformly distributed over an extended area of the surface. This same result is obtained by the control surface operating brace of the present invention. The means however of obtaining this end is different. The use of stay wires is completely eliminated; also the use of separate lever arms or horns. Instead there is provided a plate having substantially equal portions of its area arranged 20 upon opposite sides of the control surface. The plate itself is preferably of triangular form and of a length sufficient to carry its base end forwardly beyond the front beam of the control surface and its apex end rearwardly beyond the trailing beam thereof. This not only strengthens the control surface transversely but provides for the elimination of the stay wires. The base end or leading edge of the plate is reinforced 25 throughout the major portion of its length and the control leads connected at the base angles. The bracing means not only prevent transverse distortion of the plate but it strengthens it at the leading edge and in 30 the direct vicinity of the points of attachment of the control leads. Further constructional features of the operating brace or yard-arm will be hereinafter set forth. It is sufficient to state that the construction 35 of the plate is such that the control surface is strengthened without undue resistance and

at a point where maximum strength is required.

Of the drawings:

Figure 1 is a plan view of the rudder operating brace showing its attachment to the rudder. 55

Fig. 2 is an enlarged transverse sectional view of the rudder.

Fig. 3 is an edge view of the control base, 60 and

Figs. 4, 5, 6 and 7 are enlarged sectional views on the lines 4-4, 5-5, 6-6 and 7-7 of Fig. 2.

The invention, although described as a 65 rudder operating brace, is equally as well applicable to any and all control surfaces of an airplane. It is intended to supplant the lever arms or horns of airplane control surfaces.

In Fig. 1 the rudder operating brace designated in its entirety by the numeral 10 is shown as attached to the rudder 11 of an airplane (not shown). The rudder is in turn mounted in direct continuation of the 75 vertical fin or stabilizer 12 to which it is hinged as at 13 for lateral swinging movement. The rudder itself comprises the usual front beam 14 and rear beam 15, the latter in the embodiment illustrated lying 80 somewhat ahead of the trailing edge of the rudder. Web strips 16 extend at right angles to the beams 14 and 15 and with cap strips 17 constitute the rudder frame-work. In the embodiment illustrated only the web 85 strips and cap strips lying in the immediate vicinity of the control brace are shown.

The control brace or yard arm in its preferred embodiment comprises a substantially triangular plate 18 having lightening 90 holes 19 of suitable size formed in it. The triangular form of the plate is that of an isosceles triangle, the base of the triangle being forwardly located to bisect the front beam 14 of the rudder. Substantially equal 95 portions of the total area of the plate 18 lie upon opposite sides of the rudder as indicated in Fig. 2.

At the base end of the triangular plate 18 a recess or opening 20 is provided. The 100 size of this recess is dependent upon the cross sectional area of the front rudder

beam 14. The rudder beam is fitted in the recess and the plate 18 is attached to the beam by opposed angle plates 21. These angle plates are opposed not only with respect to the plate 18 but with respect to the beam 14 as well.

Another and somewhat similar opening 22 is formed in the plate 18 at or near its apex end. Through this opening the rear or 10 trailing rudder beam 15 extends. As an attaching means ears 23 are struck out from the plate 18 to lie flat against the beam 15 to which they are fastened as indicated at 24. There is thus provided a fastening at 15 the leading edge of the rudder (to the front beam 14) and also at a point distantly removed therefrom. The result is that the rudder is transversely braced and the operating stress occasioned by the manipulation 20 of the control leads distributed over an extended area of the rudder.

The control leads, designated as 25, are fastened respectively at opposite edges of the plate 18 and preferably at the base angles thereof. From the points of attachment of the control leads inwardly the plate 18 is reinforced by opposed metallic tubing 26 split longitudinally and brazed to the leading edge of the plate. This reinforcing 30 means effectually prevents transverse distortion of the plate and strengthens it laterally out from the beam 14 to the points of attachment of the control leads where added strength is most needed. At the points of 35 attachment of the leads 25 with the plate 18 washers 27 are provided. These washers are brazed on and preferably provided upon the opposite faces of the plate to strengthen it and at the same time to constitute eyes for 40 the attachment of the control leads 25. If desired, the metallic tubing 26 may be provided with a filler or core 26' for added strength.

The plate, it will be noted, is constructed 45 in one piece and extends uninterruptedly through the rudder surface. For that portion of its area, defined by the thickness of the rudder, it is faced by the web strip 16 and cap strip 17, the web strip being riveted 50 to the plate as indicated at 28 at several points to strengthen the rib and better distribute the operating strains over the full area of the rudder.

If desired, the plate 18 may be covered 55 with suitable fabric so that the lightening holes 19 will not be apparent. This would tend to minimize head resistance although the fabric, in the drawings is not shown. Moreover, the length of the plate may be 60 increased and its apex end carried back to the trailing edge of the rudder. This however is unnecessary where the rudders are provided with what are designated as trailing beams which are forwardly removed 65 from the trailing edge of the rudder.

While I have described my invention in detail in its present preferred embodiment, it will be obvious to those skilled in the art after understanding my invention that various changes and modifications may be made 70 therein without departing from the spirit or scope thereof. I aim in the appended claims to cover all such modifications and changes.

What is claimed is:

1. In an airplane, the combination with a 75 control surface, of an operating brace extended through the control surface at substantially a right angle, said operating brace having its leading edge concaved, the point of maximum concavity lying closely adjacent the leading edge of the control surface.

2. An operating brace for airplane 80 control surfaces comprising a plate extended through the control surface for presentation 85 edge-wise to the air, the depth of the plate in a fore and aft direction exceeding its width and being at least equal to the distance between the leading and trailing beam of the control surface, said plate at opposite 90 sides of the control surface and along its leading edge being extended forwardly and outwardly at an angle.

3. An airplane control surface operating 95 brace comprising a substantially triangular plate having equal portions of its area disposed respectively at opposite sides of the control surface together with means reinforcing the base end of the plate throughout the major portion of its length whereby the 100 plate in its entirety is held against transverse distortion.

4. An airplane control surface operating 105 brace comprising a substantially triangular plate extended through the control surface 110 and having substantially equal portions of its area arranged respectively at opposite sides thereof, the marginal edges of the plate diverging inwardly from points directly opposite the leading edge of the control surface, the degree of divergence in each instance being such that the edges of the plate define angles less than a right angle.

5. In an airplane, the combination with a 115 control surface, of an operating brace extended through the control surface at substantially a right angle, said operating brace having its ends recessed to receive structural 120 elements of the control surface.

6. An airplane control surface operating 125 brace comprising a plate having substantially equal portions of its area arranged respectively at opposite sides of the control surface, said plate being provided at or near its leading edge with a recess or opening into which the front beam of the control surface is fitted.

7. An airplane control surface operating 130 brace comprising a plate having substan-

- tially equal portions of its area arranged respectively at opposite sides of the control surface, said plate being provided at, or near its apex end with a recess or opening within 5 which the trailing beam is fitted.
8. An airplane control surface operating brace comprising a plate having substantially equal portions of its area arranged respectively at opposite sides of the control 10 surface, said plate being provided with recesses or openings respectively at or near its leading edge and apex end for the reception of the front beam and trailing beam of the control surface respectively.
- 15 9. An airplane control surface operating brace comprising an isosceles triangular plate having substantially equal portions of its area arranged respectively at opposite sides of the rudder, said plate having a gradually decreasing width from front to rear 20 and an over-all length sufficient to overlap respectively the front beam and the trailing beam of the control surface, means rein-
- forcing the base end of the triangular plate to prevent its transverse distortion, and 25 means for fastening the plate to the control surface at its base end and apex end respectively.
10. An airplane control surface operating brace including in combination with the 30 beams and ribs of the control surface, a substantially triangular plate having its apex end extended beyond the trailing beam and its base end extended beyond the leading beam of the control surface, said plate, intermediate its base end and apex end being reinforced longitudinally by the webs of the control surface.
11. Airplane control surface operating equipment including a one piece metallic 40 plate extended through the control surface for projection beyond its opposite faces.

In testimony whereof I hereunto affix my signature.

WILLIAM STARLING BURGESS.
